INVENTOR
John Henry Rosa

UNITED STATES PATENT OFFICE.

JOHN HENRY ROSS, OF TORONTO, ONTARIO, CANADA.

ELECTRIC HEATER.

Application filed August 5, 1921. Serial No. 489,989.

To all whom it may concern:

Be it known that I, JOHN HENRY Ross, of 651 Yonge Street, in the city of Toronto, in the county of York and Province of Ontario, Dominion of Canada, have invented 5 certain new and useful Improvements in Electric Heaters, of which the following is a specification.

My invention relates to an electric heater 10 of the type used in air drying machines and similar devices where a continuous current is blown or drawn through the heater at a velocity which permits of only that part of the current being heated which has direct 15 contact with the resistance wire; the object of the invention being to so devise the heater that the whole of the moving air must at some stage of its progress, come into direct contact with the resistance wire and be instantaneously and uniformly heated to the 20 desired degree, regardless of its volume or velocity.

In carrying out my invention I use a specially constructed core which enables the resistance wire to lie diagonally to and across 25 the axis of the moving current.

In the preferred construction, the core of the heater consists of a set of longitudinally arranged and radially spaced insulators 30 tapered lengthwise of the heater and rigidly held in fixed position by a corresponding set of insulator holding members or arms and the resistance wire is spirally wound on the insulators to lie diagonally to the axis of 35 the heater and present a heating surface across the path of the current into direct contact with which the air must come as it flows through the heater.

In heaters where two or more degrees are 40 required, the core may consist of a plurality of similar tapered sections or units with the resistance wire of each section or unit concentric with the longitudinal axis of the heater and diagonal to the path of the air 45 current passing through it.

To confine the air current in contact with the resistance wire an insulated casing is employed to enclose the heater, the internal diameter of the casing being but slightly 50 greater than the maximum diameter of the tapered core.

In the drawings;

Fig. 1, is an elevation of the heater.

Fig. 2, is a central vertical section of Fig. 55 1, taken on the line $x-x$, and

Fig. 3, is a horizontal section of Fig. 1 taken on the line $y-y$.

Referring to the drawings, it will be seen that the skeleton holding frame is arranged as follows:—1 is the upper end plate or disk 60 having a central insulating zone 2 through which the feed wires 3, 4, and 5 pass.

6 is the lower end plate or disk and between this and the upper disk 1 are rigidly attached the longitudinal insulator holding 65 members or arms 7. These arms 7 are radially arranged upon their supporting end plates or disks 1 and 6, and are stepped or serrated lengthwise at intervals to provide a plurality of tapering sections 8. These longitudinal holding members or arms 7 are of U-shape cross-section and embrace and rigidly hold the insulator strips 9. The strips 9 are of corresponding shape and taper in a similar manner to the holding members or arms 7 and their edges are provided with a series of spaced notches 10, for the reception and retention of the resistance 70 wire 11.

The serrated formation of the insulator strips 9 provides a plurality of similar tapered sections or units 9' with the spirals or coils of the resistance wire of each section or unit concentric with the longitudinal axis of the core and the perimeters of the spirals or coils in a plane tangential thereto and diagonal to the path of the air current passing through the heater, thereby presenting a heating surface transversely across the entire path of the current and instantaneously 80 and uniformly heating the whole of the moving air by direct contact with it.

The resistance wire 11 is wound spirally around the serrated insulator strips 9 and retained in position by the spaced notches 10, being connected to the feed wires 3 and 4. An intermediate connection with the resistance wire 11 is made with the feed wire 5 which is preferably connected as shown, at a point equidistant from the connections 85 with the feed wires 3 and 4. At spaced intermediate points in the central bore of the skeleton frame are immovably fixed spacing disks 13. The construction hereinbefore described is enclosed within the casing 12, the 90 internal diameter of which is but slightly greater than the maximum diameter of the core to confine the air in close contact with the resistance wire as it flows through the heater, the air passing over the first heating 105 110

cone is heated, and is repeatedly reheated on coming in contact with each successive resistor cone, finally reaching a desired predetermined temperature, this arrangement effecting a direct contact with the air with the resistance wire and enabling every thermal unit to be effective in raising the temperature of the contacting air.

Having now particularly described and ascertained the nature of my said invention and in what manner the same is to be performed, I declare that what I claim is:—

1. In an electric heater element an insulated core comprising an insulator consisting of a plurality of tapering insulator sections, electric resistors disposed upon said sections, to heat and repeatedly reheat a current of air contacting with said resistors.

2. In an electric heater element, an insulated core comprising a set of spaced insulators each of which is stepped lengthwise at intervals to provide a plurality of taper-

ing insulator sections, electric resistors disposed upon said sections, to heat and repeatedly reheat a current of air contacting with said resistors.

3. In an electric heater element, an insulated core comprising a set of supporting end plates, a set of arms radially arranged on said end plates and each stepped lengthwise at intervals for forming a plurality of tapering sections, and a set of insulators held by said arms and each of which is stepped lengthwise at intervals for forming a plurality of tapering insulator sections, electric resistors disposed upon said sections, to heat and repeatedly reheat a current of air contacting with said resistors.

Dated at the city of Toronto, this 16th day of July, A. D. 1921.

JOHN HENRY ROSS.
